[57] **CLAIM**

The ornamental design for a file box, as shown and described.

DESCRIPTION

FIG. 1 is a perspective view of a file box showing our new design;

FIG. 2 is an elevational view of one side thereof, the opposite side being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a top plan view thereof with the file box opened;

FIG. 8 is a perspective view of a second embodiment of our new design, illustrating a file box with a handle;

FIG. 9 is a top plan view of the file box of FIG. 8;

FIG. 10 is an elevational view of one side of the file box of FIG. 8, the opposite side being substantially a mirror image thereof;

FIG. 11 is a front elevational view of the file box of FIG. 8;

FIG. 12 is a rear elevational view of the file box of FIG. 8;

and,

FIG. 13 is a bottom plan view of the file box of FIG. 8.
